UNITED STATES PATENT OFFICE.

FRANK JORDAN, OF NEW YORK, N. Y.

ARTIFICIAL MINNOW.

1,361,067.

Specification of Letters Patent. Patented Dec. 7, 1920.

Application filed January 10, 1916. Serial No. 71,348.

To all whom it may concern:

Be it known that I, FRANK JORDAN, of New York, in the county of New York and in the State of New York, have invented a certain new and useful Improvement in Artificial Minnows, and do hereby declare that the following is a full, clear, and exact description thereof.

My invention relates particularly to "minnows" or "plugs" used in fishing.

The object of my invention is to provide a device of this character, which may be used in trolling in the line of movement of the boat, if desired, but which may also be used so as to maintain the minnow in the water at a distance to either one or the other side of the path of movement of the boat. It is particularly advantageous to provide a minnow or lure so that it can be conveyed through the water at one side of the path of movement of the boat, as many fish are frightened away by the movement of the boat, and, in fact, only the least desirable fish may be caught by trolling in the water which has been disturbed by the passage of the boat. In fact, as the boat passes along through the water the most desirable game fish pass to one side or the other of the boat so as to be away from the path of movement thereof. Previously, when it was desired to catch fish at a distance from the boat on one or the other sides thereof, it was necessary to accomplish the same by casting, that is to say, throwing a lure by means of a short rod having a line and a reel. This is very laborious indeed, and requires a great degree of skill, and is very wearing on the tackle. My invention obviates the necessity of such casting. My device is, in effect, a dirigible minnow and top water lure, and it can be sent out for great distance to either side of the boat because of the nature of its construction. It can readily be guided by the rod or reel so as to pass along the edge of lily pads, reeds, rocks, stumps, etc., where the most desirable fish, especially bass, are likely to be, and where they would be undisturbed by the noise, shadow, or movement of the passing boat. The operation of the minnow, furthermore, does not require any violent movements of the rod and tackle, as in the case of casting, which would tend to frighten away the fish.

A further object of my invention is to provide an artificial minnow which is flat in

shape, so as to give the necessary stability, and thereby avoid the rotation of the minnow in the water, and so as to provide frictional resistance to deflect it away from the path of movement of the boat. By arranging the minnow so that it does not revolve in the water there is no danger of twisting or kinking the line in the water, even though no swivels are used. In my minnow, furthermore, the fish line may be attached directly to an eyelet in the minnow without using any bridle, it being advantageous to avoid bridles, as the latter tend to cause the minnow to dive.

While my invention is capable of embodiment in many different forms, for the purposes of illustration I have shown only one form thereof in the accompanying drawings, in which—

Figure 1 is a bottom plan view of the minnow,

Fig. 2 is a vertical section of the same on a line passing through the fin recesses.

In the drawings I have shown a block 1 which is preferably larger at its front end than at its rear end, and having in general the shape of a minnow, and which may, if desired, be made of some material lighter than water, as, for example, wood. It may be provided on the out side with any desired color, as, for example, a thick coating of paint 2. At its front or larger end, the block 1 carries an eyelet 3 for the attachment of a fishing line when the device is used for trolling behind the boat. At the other end the block 1 is provided with an eyelet 4 to which there is attached any suitable set of fish hooks 5. At one side, the block 1, furthermore, is provided with an eyelet 6, to which the line is attached when the minnow is to be used in the water at one side of the path of movement of the boat. In the body of the block there are preferably provided forward and rear fins 7 and 8, which preferably have slots 9 and 10 through which pass pins 11 and 12 in such a manner as to permit vertical movement by gravity of the fins 7 and 8. The size of the fins is preferably such that when the ends of the slots 9 and 10 rest upon the pins 11 and 12, the fins will be flush with one face of the block 1, while the unslotted portions of the fins 7 and 8 will project beyond the opposite face of the block and serve to guide the minnow at one side of the boat and at a distance from the path there-

of. It will, furthermore, be noted that the fins 7 and 8 are located angularly with regard to each other, so that they will tend to continually move the block 1 outwardly 5 away from the path of movement of the boat when the fishing line is attached to the side eyelet 6.

In the operation of my invention, the minnow may be used for trolling in the usual 10 way, by merely attaching the line to the front eyelet 3. When desired, however, the minnow may be used so as to operate in water at either side of the path of movement 15 of the boat by merely attaching the line to the side eyelet 6 and then throwing the minnow into the water at one side of the boat. When this has been done the fins 7 and 8 will fall downwardly until they extend below the lower face of the block 1, and in this position 20 they will effectively guide the minnow to the water located at a distance from the path of movement of the boat. If it is desired to change the lateral direction of movement of the minnow, this may be done by simply turning 25 over the latter in the water, so that the angle of fins 7 and 8 with respect to the longitudinal axis of the minnow is reversed. In practice, it has been found that the minnow 30 can be made to take a position as far as forty (40) feet away from the path of movement of the boat. As the boat proceeds through the water, the minnow is conducted along the surface of the water at the desired 35 distance from the boat, and the minnow may be guided at will among any objects in its vicinity merely by increasing or decreasing the pull upon the line attached to the eyelet 6. If it is desired to operate in the water on the other side of the boat, the minnow is 40 thrown into the water at that side, and when this is done, the fins 7 and 8 may be made to fall through the body of the block 1, by throwing the minnow far enough to the side of the boat and then pulling sharply on the 45 line so that they extend beyond the opposite side to that which they occupied when the block was used on the other side of the boat, as above described. Owing to the fact that the tops of the fins 7 and 8 are flush with the 50 surface of the block, the block will not be influenced by the wind. Furthermore, the relative angular positions of the fins 7 and 8 will at all times tend to maintain the minnow far away from the path of movement of the

boat, and subject to the will of the fisherman 55 through the increase or decrease of the pull upon the line attached to the eyelet 6.

While I have described my invention above in detail, I wish it to be understood that many changes may be made therein without 60 departing from the spirit of my invention.

I claim:

1. A trolling minnow having a vertical and vertically movable inflexible, slotted fin inclined to the longitudinal axis of the 65 minnow.

2. A trolling minnow having a vertical and vertically movable inflexible, slotted fin inclined to the longitudinal axis of the minnow, the construction being such that the 70 angle of inclination of said fin may be reversed.

3. A trolling minnow having a plurality of vertical and vertically movable inflexible, slotted fins oppositely inclined to the longitudinal axis of the minnow. 75

4. A trolling minnow having a plurality of vertical and vertically movable inflexible, slotted fins oppositely inclined to the longitudinal axis of the minnow, the construction being such that said angle of inclination 80 may be reversed.

5. A trolling minnow having a vertical and vertically movable inflexible, slotted fin thereon, the construction being such that said fin 85 may be adjusted to extend beyond either face of said minnow.

6. A trolling minnow having a plurality of vertical and vertically movable inflexible, slotted fins oppositely inclined to the longitudinal axis of the minnow, the construction 90 being such that said fins may be adjusted to extend beyond either face of the minnow.

7. A lure comprising a body portion, and means acting upon said portion adjustable by 95 inversion of the body portion to cause the lure to follow a path of motion at either side of the path of motion of the member moving the lure.

8. A trolling minnow having in its body 100 portion a pair of vertical slots oppositely inclined to the longitudinal axis of the minnow, and a pair of vertical fins slidably mounted in said slots.

In testimony that I claim the foregoing I 105 have hereunto set my hand.

FRANK JORDAN.
